(57) **CLAIM**

The ornamental design for the connector for poles, as shown and described.

DESCRIPTION

FIG. 1 is a perspective view of a connector for poles showing my new design;

FIG. 2 is a front elevational view thereof;

FIG. 3 is a top plan view thereof, with a bottom plan view being a mirror image thereof;

FIG. 4 is a right side elevational view thereof;

FIG. 5 is a left side elevational view thereof; and,

FIG. 6 is a bottom plan view thereof.

The broken lines showing display poles and paddle are for illustrative purposes only and form no part of the claimed design.
